UNITED STATES PATENT OFFICE.

THEODORE PARKER BROWN, OF WORCESTER, MASSACHUSETTS.

DESIGN FOR A CASE OR CABINET FOR MUSICAL INSTRUMENTS.

SPECIFICATION forming part of Design No. 34,384, dated April 16, 1901.

Application filed March 8, 1901. Serial No. 50,400. Term of patent 14 years.

To all whom it may concern:

Be it known that I, THEODORE PARKER BROWN, a citizen of the United States, residing at Worcester, in the county of Worcester 5 and State of Massachusetts, have invented and produced a certain new and original Design for a Case or Cabinet for Musical Instruments; and I do hereby declare the following to be a full, clear, and exact description of the invention, such as will enable others skilled in the art to which it appertains to make and use the same.

This invention relates to a new and original design for a case or cabinet for musical 15 instruments, such as are commonly known as "piano-players."

The invention is illustrated in the accompanying drawing, wherein the figure represents in perspective a case or cabinet for a 20 piano-player embodying the essential features of the design.

The base or supporting structure for the case proper consists of two end pieces 1 1, connected together by connecting-pieces 2 2, 25 and rising from each end piece, as shown, are two legs or columns 3 3, terminating at their upper ends in ornamental caps 4 4. Surmounting the four legs or columns 3 3 is the case proper, 5, which is substantially rectan-

gular in shape, and rising from the case 30 proper is a housing formed by the end boards 6 6, top board 7, and front wall or board 8. The two end boards 6 are each provided with cut-out portions 9 at their rear immediately above the case proper. 35

Located above the case proper and forming a forward extension of the front wall or board 8 is a hood-like extension formed by the end walls 14, curved or convexed front sections 15, and intermediate convex wall 16. 40

The leading or characteristic feature of the design is a case or cabinet for musical instruments having an open base or supporting structure provided with legs or columns surmounted by a case proper substantially rectangular in shape and having a housing rising therefrom, as shown. 45

What I claim is—

The design for a case or cabinet for musical instruments, substantially as herein shown 50 and described.

In testimony whereof I affix my signature in presence of two witnesses.

THEODORE PARKER BROWN.
